B. H. SCOTT

CEMENT DUMP

Filed Feb. 3, 1923

INVENTOR.
BERNARD H. SCOTT.

Pittsburgh
HIS ATTORNEY.

UNITED STATES PATENT OFFICE.

BERNARD H. SCOTT, OF GLENDALE, CALIFORNIA.

CEMENT DUMP.

Application filed February 3, 1923. Serial No. 616,865.

To all whom it may concern:

Be it known that I, BERNARD H. SCOTT, a citizen of the United States, residing in the city of Glendale, county of Los Angeles, 5 and State of California, have invented certain Improvements in Cement Dumps, of which the following is a specification.

My invention relates to devices for discharging mixed cement, in any quantity, in 10 the bottom of a well without allowing it to fall any considerable distance. My device is adapted to be attached to the lower end 15 of a pipe or casing which may be of any desired length and filled with the mixed cement and let down into the well until it reaches the bottom, whereupon the device is tripped and all the cement in the pipe is allowed to run out as the pipe and the device are withdrawn from the well. The principal object of my invention is to provide a 20 device of the character referred to which is simple, practical and durable, with a minimum number of parts to get out of order and be replaced.

25 In order to describe my invention, I have shown on the accompanying sheet of drawings one practical embodiment thereof, which I will describe in detail. In the drawings,—

30 Figure 1 is a longitudinal sectional view of a device embodying my invention;

Figures 2, 3, 4, 5 and 6, are cross sectional views taken on the lines 2—2, 3—3, 4—4, 5—5, and 6—6, respectively, of Fig. 1.

35 Figure 7 is a view similar to Fig. 1, showing the parts in the dumping or discharging position.

Referring now in detail to the drawings, 1 designates a pipe or casing to which my 40 device can be attached. My device comprises a casing or body member 2, having its lower end beveled, as at 2^a, and its upper end threaded for attachment to a pipe 1, as shown. The body 2 is provided internally with a disc-like portion, 3, with a central opening, 3^a, and a series of openings 3^b, as indicated clearly in Fig. 3. Mounted through the central opening 3^a of said member 3, is a tubular member 4, having at its 45 upper end a collar, 5, the upper end of

which is beveled, as at 5^a. Slidably mounted through said tubular member 4 and said member 5, is a shaft 6, having at its upper end a head 6^a, the under side of which is beveled, as at 6^b, to fit the beveled upper end 55 of the member 5, and to seat therein, as indicated in Fig. 1. The lower end of said shaft 6 is provided in its opposite sides with longitudinally extending slots or channels, as 6^c, which are deeper at 6^d. At its lower 60 extreme end said bolt is provided with a nut 7. The tubular member 4, within the body 2, and below the part 3, is provided with an annular shoulder member 4^a, the upper side of which is square, as at 4^b and the underside of which is beveled, as at 4^c. The lowermost end of said tubular member 4 is provided with a threaded nut or collar 4^d. Around the tubular member 4 is placed a coupling member 8, having right hand and 65 left hand threads, as at 8^a, and 8^b, and with a middle disc-like part 8^c for turning the same. On the upper end of said member 8, is a conical member 9, having a beveled part, 9^a, to fit the beveled underside 4^c of 70 the part 4^a, and also having a beveled part 9^b to fit and fill the lower end of the body member 2, as clearly indicated in Fig. 1. On the lower end of said member 8, is another conical member 10, having its lower 75 outside slightly conical, as at 10^a and its lower inner opening beveled, as at 10^b, and adapted to receive the outer parts of two keys, 11, seated in the shaft 6, and extending through openings in the tubular member 4, as clearly indicated in Fig. 1, and 80 from Fig. 7. When the parts are assembled, as in Fig. 1, the lower end of the body member 2 is closed and mixed cement put into the pipe 1, from the upper end will pass 85 down through the openings 3^b and fill the body member 2, resting on the conical member 9, and can extend up into the pipe section 1 as far as desired, depending upon the quantity of cement desired for one 90 charge.

With the parts thus assembled and the cement mixture loaded into the casing as referred to, the whole thing is lowered into the well until the lower end of the shaft 100

6, strikes the bottom of the well, whereupon it is forced upwardly through the tubular member 4, until the deeper channels 6^a therein come opposite the keys, 11, 11, and said 5 keys fall back into said channels, and release the parts, 8, 9 and 10, allowing them to drop down away from the lower end of the body 2, and the charge of mixed cement runs out as the casing and device are 10 drawn up again from the well.

As the parts 8, 9 and 10 are assembled, the part 8 is turned to force the parts 9 and 10 apart and to firmly seat the part 9 15 in the lower end of the body 2, and the part 10 on the keys 11. These parts move as a unit, as seen in Fig. 7, when they are tripped in the manner described.

Thus I have described one practical embodiment of my invention, and while it is 20 possible to make changes in the details of construction and arrangement here shown for illustrative purposes, I do not limit my invention to the showing made, except as I may be limited by the hereto appended 25 claims.

I claim:

1. In a device of the character described, in combination, an outer casing member, an 30 inner tubular member of less diameter to provide an annular space between said outer and inner members, means holding said inner tubular member in place in said outer member, a closure member around said inner tubular member at the lower end of said 35 outer casing member, a shaft member in said inner tubular member, and means controlled by said shaft and said inner tubular member for holding said closure member in closing position in the lower end of said 40 outer casing member, said means being adapted to be released by the movement of said shaft inwardly.

2. In a device of the character described, in combination, an outer casing member, an 45 inner tubular member of less diameter to provide an annular space between said members, means holding said inner member in place, a closure member around said inner tubular member at the lower end of said 50 outer member, a shaft extending through said inner tubular member and said closure member and extending beyond the same, holding members interposed in said shaft, said inner tubular member and said closure 55 member for holding the latter in closed position in the lower end of said outer casing member, and means whereby the movement of said shaft inwardly through said tubular member releases said holding members and 60 permits said closure member to move away from the lower end of said outer casing member.

3. In a device of the character described, in combination, an outer member adapted 65 to be attached to a casing, an inner member

therein of less diameter to provide an annular space therebetween, means holding said inner member in place therein, a closure member around said inner member and closing the lower end of said annular space 70 between said outer and inner members, said closure member being movable on said inner member away from said outer member, tripping means holding said closure member in closing position to close the lower end of 75 the annular space between the outer and inner members, and means adapted to engage the bottom of a well as said device is lowered therein for releasing said tripping means, whereby to permit said closure member to move away from said outer member and permit said outer member to open, for 80 the purpose indicated.

4. In a device of the character referred to, in combination, an outer casing member 85 having an inner disc-like part with a central opening therethrough and with passage openings therethrough around said central opening, an inner member extending through said central opening and providing 90 an annular space between said outer member and said inner member, a closure member around said inner member in the lower end of said outer member to close the lower end of said annular space, holding means 95 for holding said closure member in closed position, and means adapted to be moved inwardly as said device is lowered onto the bottom of a well for releasing said holding members and said closure member, whereby 100 to open the lower end of said outer casing member, substantially as described.

5. In a device of the character referred to, in combination, an outer casing, an inner tubular member, spaced therefrom and forming an annular space between said members, a shaft through said inner tubular member and extending beyond the lower end thereof, a closure member around said inner tubular member, in the lower end of 105 said outer casing, holding members in said inner tubular member and shaft and projecting from said inner tubular member for holding said closure member in closing position in the lower end of said outer casing, and means whereby the movement of said 110 shaft inwardly through said inner tubular member releases said holding members and said closure member to open the lower end of said outer casing member, substantially 115 as described.

6. A cement dump of the character referred to comprising an outer casing, an inner tubular member, means holding it spaced therein to form an annular space between said outer casing and said inner tubular member, said means permitting matter to pass therethrough in said annular space, a closure member around said tubular member at the lower end of said outer 120 125 130

casing, said tubular member comprising two threaded members and an intermediate threaded member on which said two threaded members are threaded, for adjustment 5 and moving as a unit, key members for holding said closure member in position to close the lower end of said outer casing, and a shaft for releasing said key members to

release said closure member, substantially as shown and described.

Signed at Casper, Natrona County, Wyoming, this 20th day of January, 1923.

BERNARD H. SCOTT.
